UNITED STATES PATENT OFFICE.

MARIUS PAUL OTTO, OF PARIS, FRANCE.

DIRIGIBLE TORPEDO.

1,154,427.

Specification of Letters Patent. Patented Sept. 21, 1915.

Application filed November 18, 1913. Serial No. 801,595.

To all whom it may concern:

Be it known that I, MARIUS PAUL OTTO, citizen of the Republic of France, residing at No. 44 Avenue du Bois de Boulogne, Paris, France, have invented certain new and useful Improvements in Dirigible Torpedoes, of which the following is a specification.

This invention has for its object a torpedo so constructed as to be capable of being steered from a distance by means of electric waves, and more particularly by the method and apparatus described in the specification of British Patents Nos. 20789/13 and 21212/13 or in applications for U. S. Patents filed in U. S. on September 11th 1913 Serial Nos. 789323 and 789324.

A practical construction of a torpedo designed according to this invention is illustrated by way of example in the accompanying drawings, in which:

Figure 1 is a longitudinal elevation of the general arrangement. Fig. 2 is an end view thereof.

According to this invention the spindle-shaped shell *a* of the torpedo is provided with two uprights *b* constituting the supports for a float *c*, which is intended to maintain the torpedo at a distance below the surface of the water determined by the height (adjustable if desired) of the said supports *b*. From the float *c* there project uprights *b'* preferably formed by extensions of the uprights *b* and constituting antenna-carriers, that is to say, they serve to support an antenna *d* receiving waves that emanate from the controlling station. The supports *b'* may at the same time serve to carry two luminous signals *e* fed for example by means of current from a battery of accumulators carried by the torpedo. Transverse equilibrium of the float *c* may be facilitated by its connection with longitudinal planes *c'* projecting laterally from the shell *a* of the torpedo. The connection may be effected for instance by cables or rods *c''* adjustable in length, (Figs. 1 and 2).

For the purpose of steering the torpedo, the latter is provided with a steering rudder, formed by two surfaces *g', g'', g', g''* arranged in the longitudinal axial plane of the torpedo and movable about one and the same pivotal shaft *g* traversing the torpedo. The surfaces constituting the rudder comprise

each two planes *g', g''* of unequal areas, thereby insuring by the action of the liquid medium in which they are submerged, the automatic return of the said rudders into their axial position as soon as they cease to be actuated. The rudders *g', g''* are adapted to move in two outer fin-like structures, of which one *f, f'* is vertical and the other *f', f''* is horizontal.

The waves transmitted by the controlling station, for instance, by the means described in the specifications of the two earlier patents above mentioned, are received by the antenna *d* and according to the will of the operator they establish a lighting circuit or a circuit producing upon the motor (not shown) or upon the mechanisms driven by the latter, those effects which are desired for modifying the direction or the speed of travel, as well as the direction or speed of working of the several steering or other appliances, and in particular of the rudders *g', g''*. The electric waves are transmitted by the conductor *d'* to a receiving apparatus (not shown) of suitable construction such as for example the apparatus described in the specification of British Patent No. 21212/13 or in application filed in U. S. on September 11th 1913 No. 789324.

Having now described my invention what I claim as new and desire to secure by Letters Patent is:

1. A torpedo capable of being steered from a distance by means of electric waves, comprising in combination a float, supports extending therefrom in an upward and in a downward direction, a torpedo body carried by the lower supports at a determined distance below water level, an antenna carried by the upper supports, luminous signals on the latter supports, electric conductors within the supports extending from the torpedo body to the antenna and vice versa, and means projecting laterally from the torpedo body and adjustably secured to said float for imparting transverse stability to the latter.

2. A torpedo capable of being steered from a distance by means of electric waves, comprising in combination a float, hollow supports extending therefrom in an upward and in a downward direction, a torpedo body carried by the lower supports at a de-

terminated distance below water level, an antenna carried by the upper supports, luminous signals on the latter supports, electric conductors within the supports extending from the torpedo body to the antenna and vice versa, longitudinal planes projecting laterally from the torpedo body and connections from said planes to the float, for the

purpose of imparting transverse equilibrium to the float.

In testimony whereof I have affixed my signature in presence of two witnesses.

MARIUS PAUL OTTO.
